UNITED STATES PATENT OFFICE.

WILLIAM THUM, OF HAMMOND, INDIANA.

APPARATUS FOR REFINING AND DESILVERIZING LEAD.

1,106,480.

Specification of Letters Patent. Patented Aug. 11, 1914.

Application filed December 9, 1910. Serial No. 596,400.

To all whom it may concern:

Be it known that I, WILLIAM THUM, a citizen of the United States, and a resident of Hammond, in the county of Lake and 5 State of Indiana, have invented certain new and useful Improvements in Apparatus for Refining and Desilverizing Lead, of which the following is a specification.

The invention relates to the refining and desilverizing of lead bullion by crystallization processes as the Pattinson process, especially by the modification of the Pattinson process by Luce and Rozan and derivative processes generally known as "steam 10 pattinsonizing" processes. These processes separate silver, gold, bismuth and other impurities from the lead contained in the lead base bullion, by concentrating the former into one portion of the lead bullion treated, while the remainder of the lead is obtained as desilverized, soft lead in another portion.

Briefly stated, the operations in a Pattinson kettle series using other means than 15 agitation by hand and transfer of the products by hand ladles, are as follows: Lead base bullion, containing silver, is preferably melted in a special kettle or in a reverberatory furnace, with or without a preliminary 20 refining or softening, for the elimination in part, or the whole, of the copper, antimony, arsenic, etc. The liquid bullion is run into one of the central kettles of a series of 25 kettles, which are heated by any convenient means, and is there subjected to the following operations:—

First. Agitation by steam blown through the molten bath, and cooling by intermittently applying a water spray on the agitated surface of the molten bath. This operation is the crystallization period proper; and during this period the lead crystals, 30 poor in silver, are formed and sink to the bottom of the kettle as a mushy mass, the enriched alloy collecting on top as well as 35 permeating the mass of crystals.

Secondly. Removal of the liquid alloy by tapping same through one of the two spouts at the bottom of the kettle and through a 40 screen adapted to retain the crystals. The enriched alloy, amounting to about one-third of the total, is always transferred in one direction to the adjoining kettle of the 45 series, which kettle is two-thirds filled with 50 metal of the same tenor in silver from previous operations. The transfer of the alloy

is accomplished either by raising the kettle being tapped, or by lowering the receiving kettle; or, by means of large ladles moved by powerful cranes and the like.

Thirdly. Remelting of the crystals, amounting to about two-thirds of the total charge of the bullion melted, and transfer of the same to an adjoining kettle through the other of the two spouts at the bottom of 60 the kettle, but in the opposite direction to that which the enriched alloy has been transferred. This adjoining kettle is filled with impoverished lead, of the same grade, from previous operations. The transfer of the 65 melted crystals is accomplished in the same manner as the transfer of the alloy.

Finally. Repeating and continuing these operations in each kettle of the series, in both directions from the kettle taking the 70 first charge, until at one end bullion, enriched to about 500 ounces silver is produced; and, at the other end, a desilverized, soft market lead is obtained. The former product is subjected to further refining 75 treatment, usually by zinc desilverization or by direct cupellation; the latter is sold. During these operations any dross that is formed is skimmed off and is reduced in a special reverberatory or blast furnace to 80 base bullion, which is returned to the process.

My invention has for its object to simplify the method of transfer from kettle to kettle of the enriched portion of the bullion and of the melted, impoverished crystals of 85 lead; and to obtain a permanent, fixed arrangement of the apparatus on one floor level, easy of access and operation, and whereby all cumbersome and expensive mechanism to elevate the kettles in tapping 90 by gravity, or in transferring the kettle contents in ladles by hand, or by mechanical lifting appliances and the like, may be avoided.

My invention has for its further object 95 to so mount and construct the kettles that they may be readily and inexpensively interchanged or removed from their settings in case of renewal or repair.

The invention also contemplates the employment of air under high pressure, instead of steam, for the agitation of the molten mass, because of the quicker cooling of the bath of the metal, thus hastening the formation of crystals as well as more effectively oxidizing any impurities present.

The invention provides, also, for the ar-

angement of a kettle at the end of the series to which the enriched product is being transferred, and from which kettle the rich bullion containing silver, gold, bismuth and small quantities of impurities may be cast 5 into anodes suitable for subsequent electrolytic refining treatment for the recovery of the metals gold, silver and bismuth, and antimony and copper, if present.

10 The nature of my invention will be best understood when described in connection with the accompanying drawings, in which—

Figure 1 is a front elevation of a series of kettles for the lead bullion, said series communicating at each end with suitable kettles, shown in section, the kettle at one end being employed to melt and cast the refined portion of the lead into merchant bars, while from the kettle at the other end, the enriched 20 portion of the lead is cast into anodes for subsequent electrolytic refining treatment. Fig. 2 is a side elevation of a kettle and the general arrangement of the apparatus. Fig. 3 is a detail view of the air pipe connection 25 into kettle. Fig. 4 is an enlarged front elevation, partly in section, of the kettle and setting therefor. Fig. 5 is an enlarged perspective of the kettle setting. Fig. 6 is a fragmentary detail of the removable pieces 30 of shell placed over the spouts to facilitate the replacement of kettle.

Similar characters of reference designate corresponding parts throughout the several views.

35 Referring now to Fig. 1 of the drawings, 10 designates a kettle suitably mounted in a setting 11, as will hereinafter be more fully described, said kettles being arranged on one floor level and of a sufficient number, preferably ten, to effect the desired separation. Suitable pipe connections 12 and 13 are provided between the respective kettles, the pipe connection 13 affording a communication from one side of the kettle to the top of the 40 kettle containing lead of greater richness; and the pipe connection 12 affording communication from the other side of the kettle to the top of the kettle containing more impoverished lead. A flow, in different directions, of enriched and impoverished lead is 45 therefore provided for through the series of kettles. At each end of the series of lead kettles are suitable kettles 14 and 15, the former being adapted to receive the enriched portion of the lead and the latter the refined 50 portion of the lead. From the kettle 14 the rich bullion containing silver, gold, bismuth and small quantities of impurities is cast into anodes for subsequent electrolytic refining treatment to recover the metals gold, silver and bismuth, and antimony and copper if present. From the other kettle, the refined lead, after being melted therein, is cast 55 into merchant bars. The means for effecting this flow of enriched and im-

poverished lead in opposite directions, and the general construction of a kettle and its setting, are more fully shown in Figs. 2 to 6. Fig. 4 is an elevation, partly in section, of one of the units of the series of kettles and of a suitable setting therefor. These units are preferably made of cast steel, and are provided with working doors 20 through which the lead in the shape of pig or in molten condition is charged, and through 70 which, also, a spray of cooling water may be introduced. The drosses formed on the bath may be skimmed therefrom and removed through this door and through a suitable chute 21 (Fig. 2). A tilting car 22, or the like, receives this dross and is movable beneath a working platform 23 for the man employed to remove the said dross. 25 designates a supplementary door pivotally connected to the upper portion of the kettle 10, 80 and is adapted to fit over the door 20 and to be locked by means of a pin 26 and through suitable set screws 26' to securely close the said door 20 when fluid under high pressure is introduced within the kettle 10. The kettle 90 10 is provided, also, with a suitable safety valve 27 to guard against excessive pressure within the said kettle. A vent 28 of ample dimensions is provided at the top of the kettle for the dust and air, when blowing 95 and cooling the lead, as well as a valve 28' which is closed when elastic fluid pressure is applied. Furthermore, a pipe connection 29, into which is inserted a suitable valve 30, is made at the top of the kettle 10 for the 100 purpose of introducing a suitable elastic fluid under pressure within said kettle to effect the removal of the lead therefrom. The pipe connections 12 and 13 from the preceding and succeeding kettles of the series 105 are arranged to also enter the said kettle at the top. Near the bottom of the kettles is provided a pipe connection 31 for the introduction thereto of a suitable agitating medium such as air or steam, and which is 110 adapted to be distributed by means of a baffle 32 within the said kettle.

The manner of introducing the pipe connection 31 into the kettle is shown in detail in Fig. 3. An opening 33 is made in the setting for the kettle 10 and a tile bushing 34 is inserted therein. A valve bonnet 35 is suitably secured to the flange nipple 36 of the kettle; and the said nipple provides a chamber 37 communicating through a port 38 with the pipe 31. A valve steam 39 is adapted to be advanced and retracted in any suitable manner to respectively close and open an inlet 39' from chamber 37 into the kettle. The opening 33 is made of sufficient dimensions to permit the parts to be readily assembled, after which it is filled out with the tile bushing 34. This latter, also, serves to protect the valve parts and nipple against the heat of the fire. The construction thus 130

set forth affords a very simple and convenient means of introducing the agitating medium into the kettle, and brings the valve seat close to the kettle where freezing of the 5 lead is prevented. At the bottom of the kettle are suitable spouts 40 and 41 communicating with the pipe connections 12 and 13 respectively, a strainer 42 being introduced in the spout 41. The connections 10 12 and 13 are provided with suitable valves 43 to close the same, and with a bleeder 44 provided with a valve 45. A suitable gas or oil burner 46 is provided beneath the setting 10 and over an ignition block and 15 spreader 47; and, for the purpose of obtaining a uniform distribution of the heat under the kettle 10, a checker-work arch 48 is provided beneath the said kettle and against which the flame from the burners 20 is directed. Air for the combustion is supplied to the burner through a pipe 49; and the products of combustion are led off through a tile gas flue 50 passing through the setting 11, which communicates also with 25 the main flue 51, common to the series of furnaces. A manhole and working door 52 are provided in the setting 11. The kettle itself is mounted in a novel manner in the setting, so as to be readily removable for 30 replacement or repair. To this end the portions of the setting over the spouts 40 and 41 are of special tile 60 and of a width sufficient to allow the passing of the spouts when the said tiles 60 are removed. These tiles 60 35 are held in place by removable sections 61 of sheet steel and which are adapted to slide in ways 62. The sections 61 are, furthermore, held in place by straps 63; and the top of the setting is provided with a bearing 40 ring 64 upon which the flange 65 of kettle 10 is adapted to rest. This bearing ring is made in sections held together by straps 66.

The operation of my improved apparatus is as follows: The process having been started in one of the central kettles of the series and heated to the desired degree by means of the oil burner 46, water is sprayed on the surface of the charge through the working door 20 to quickly cool the mass to the critical temperature for the formation of crystals. This operation is assisted by agitating the molten mass by means of steam or air introduced through the pipe connection 31. The crystals thus formed settle to the bottom of the kettle, the enriched lead permeating the same as well as forming a layer on the top of the bath. The door 20 is then securely locked by means of the supplementary door 25, the valve 43 for the connection 12 closed and the agitating steam or air shut off. Fluid pressure is then exerted upon the molten mass by introducing air or steam, or other suitable medium, through the pipe connection 29, the pressure being sufficient 65 to strain the enriched lead through the con-

nexion 13 into the adjacent kettle, and the crystals being held back by means of the screen 42. About one-third of the enriched bullion is thus removed. The remainder, in crystallized form, is then again melted, after 70 shutting off the source of fluid pressure. When sufficiently molten, the valve 43 of the connection 12 is opened and fluid pressure again exerted upon the mass within the kettle 10, thus transferring the impoverished 75 lead into the top of the kettle at the other side. In case of any repairs to or replacement of the kettle, the same may be readily removed without destroying the entire setting by disconnecting the pipe connections 80 12 and 13 from their respective spouts 40 and 41 and removing bearing ring 64, the straps 63, sections 61 and the tiles 60. The kettle as a whole may be then lifted by suitable means. 85

The construction herein set forth provides a series of parrisonizing units from which the lead may be transferred without raising the units being tapped, or lowering the receiving one. It, furthermore, obviates the 90 use of large ladles operated by powerful cranes for this purpose. The units are all on one floor level, are readily accessible, and the transfer is effected in the most simple manner. Moreover, should any of the 95 units require repair or replacement, the construction herein disclosed affords a ready means for effecting the same without necessitating any injury to the setting for said unit. 100

I claim:—

1. An apparatus for refining impure lead, comprising: a plurality of crystallizing kettles permanently maintained in fixed position; means connecting a kettle with another of said plurality of kettles for effecting the discharge of molten metal from one to the other; and means to introduce a suitable fluid under pressure within said kettles to effect the removal of molten metal through 110 the said connecting means. 105

2. An apparatus for refining impure lead, comprising: a series of crystallizing kettles permanently maintained at the same level; means connecting the kettles for effecting the discharge of the contents of one into another; and means to introduce a suitable fluid under pressure within said kettles to effect the removal of the contents through 115 the said connecting means. 120

3. In an apparatus for refining impure lead: a melting kettle provided with spouts; and a suitable setting for said kettle, the portion of the setting over said spouts being independent of the setting proper and readily removable. 125

4. In an apparatus for refining impure lead: a melting kettle provided with spouts; a suitable setting for said kettle, the portion of the setting over said spouts being inde- 130

pendent of the setting proper and readily removable; and means to retain said removable portions of the setting in position.

5. In an apparatus for refining impure lead: a melting kettle provided at the bottom with two oppositely disposed spouts; a suitable setting for said kettle, comprising a main portion and removable portions, the latter consisting of a plurality of blocks of fire resisting material mounted over said spouts, sheet steel sections about the outer

side of said blocks to retain the same in position, and ways connected with the main portion of the setting within which the said sheet steel sections are adapted to slide.

Signed at Hammond, in the county of Lake and State of Indiana this 6th day of December A D 1910.

WILLIAM THUM.
